VACUUM CLEANER

Osmund Holm-Hansen, Stratford, Conn., assignor
to General Electric Company, a corporation of
New York

Application March 22, 1935, Serial No. 12,357

16 Claims. (Cl. 15—16)

The present invention relates to vacuum cleaners of the type having a centrifugal separator for separating the dust from the air.

The object of my invention is to provide an improved construction and arrangement in a vacuum cleaner of this type. For a consideration of what I believe to be novel and my invention, attention is directed to the accompanying description and the claims appended thereto.

10 In the accompanying drawing, Fig. 1 is a side elevation of a vacuum cleaner embodying my invention; Fig. 2 is a top plan view of the vacuum cleaner; Fig. 3 is an enlarged sectional elevation of the vacuum cleaner; Fig. 4 is a sectional view taken on line 4—4 of Fig. 3; and Fig. 5 is a fragmentary elevation of a modification of my invention.

Referring to the drawing, the numeral 1 indicates the outer casing within which an electric 20 motor-driven fan is mounted. The electric motor comprises a stationary member 2 which is resiliently supported on the outer casing by rubber bushings 3. The rubber bushings are secured intermediate their ends in openings 4 in the outer 25 casing, and the weight of the motor is transmitted to these bushings by bolts 5. At the upper end of the stationary member 2 is a rubber ring 6 which resiliently centers the upper end of the motor within the outer casing and also seals the 30 space between the upper end of the motor and the casing. The rotating member 7 of the electric motor is carried on a shaft 8 which is journaled in upper and lower bearing housings 9 and 10 respectively. The lower end of the shaft 8 projects through the bearing housing 10, and to the projecting end of this shaft is secured a centrifugal fan 11 which may be of any suitable construction. A plate 12 which is secured to the lower end of the outer casing by a rubber band 13 provides the bottom wall of the fan housing.

The bearing housing 10 and a flange 14 on the lower end of the stationary member 2 provide the upper wall of the fan housing. The inlet to the fan housing is provided by a central opening 45 15 in the plate 12. The air is discharged around the periphery of the fan and flows upwardly through the space between the stationary member 2 and the outer casing 1 and through openings 16 which are spaced around the outer casing. From these openings, the air is directed downwardly in the direction indicated by the arrow 50 by a cylindrical baffle 17 which is spaced from and surrounds the outer casing and which extends below the openings 16. This baffle is 55 threaded on a flange 18 which extends from the

outer casing. To the lower end of the baffle is fixed a rubber ring 19 of circular cross section. This rubber ring decreases the noise caused by the discharge of air past the lower end of the baffle. At the upper end of the outer casing 1 5 is a cord reel 20 on which the cord for supplying current to the electric motor is wound. The cord is guided to the reel by a guide 21 which is carried by the baffle 17. A handle 22 is provided above the cord reel. 10

The vacuum cleaner is provided with a centrifugal dust separator which comprises a cylindrical casing 23 having a tangentially directed air inlet 24 at the upper end to which a suction hose 25 is connected. The side walls of the casing taper downward and outward and at the lower end are provided with a curved flange 26 which rests on the inturned curved edge 27 of a dust receptacle 28. A pair of rear supporting wheels 29 are carried on the dust receptacle on shaft 30, and a caster 31 is carried on the dust receptacle at the front in a bracket 32. The casing 23 is removably held in place on the dust receptacle by clamps 33 of suitable construction. 15 20

Secured to the upper edge of the casing 23 is the upper end of a tubular rubber sleeve 34. The sleeve depends within the casing and the lower end of the sleeve is provided with an in-turned flange 35 on which rests the out-turned flange 36 of a hollow discharge member. The rubber ring 13 of the motor-driven fan unit rests on top of the flange 36. By this arrangement, the motor-driven fan unit is resiliently supported on the casing 23 by the rubber sleeve 34. This unit is fastened to the rubber sleeve 34 by suitable latches (not shown) and the unit can be removed by lifting from the flange 35 after these latches are released. 25 30 35

Below the flange 36 of the hollow discharge member is a filter pad 37 which rests on a shoulder 38 on the inside of the discharge member. Below the filter pad the side walls of the discharge member taper inwardly and at the center are connected to a depending tube 39. This tube is provided with longitudinal slots 40, as shown in Figs. 3 and 4. These slots are formed by cutting a slit in the side wall of the tube and forcing the material on one edge of the slit inwardly, as shown in Fig. 4. During the operation of the cleaner, the air is whirling in the direction shown by the arrow in Fig. 4 and it is therefore necessary that the air make a sharp turn of somewhat more than 90 degrees in order to pass through the slots 40. All except the finest particles of dust which may be carried by the air 50 55

whirling around the tube 39 are not able to make this sharp turn and are thrown outward by centrifugal force, and these slots therefore provide an arrangement for centrifugally separating the 5 dust from the air. The tube 39 is open at the lower end. A plate 41 is hinged to the lower end of the tube and when the cleaner is not in use, it is biased by gravity to the position shown in dotted lines in Fig. 3. When the cleaner is in 10 use, the plate 41 is lifted by suction to close the opening in the lower end of the tube. At the conclusion of the operation of the cleaner, the plate 41 returns to the dotted line position, and any fine dust which may have accumulated within 15 the tube 39 falls through the open end of the tube into the dust receptacle.

In Fig. 5 is shown at 41a a modification of the construction of the plate 41 in which the plate is of somewhat larger diameter and is fixed to the 20 lower end of the tube 39, closing the lower end of the tube. The plate 41a prevents upward flow of air above the center of the dust receptacle which would produce air currents interfering with the whirling motion of the air and thereby interfering with the centrifugal separation of the 25 dust from the air.

When the cleaner is not in use, the hose 25 is coiled around the outside of the casing 23, as shown in dotted lines in Fig. 1, and is held in 30 place by a hook 42 extending from the casing 23.

In the use of the vacuum cleaner, the hose 25 is uncoiled from around the casing 23 and is connected to a suitable cleaning tool 43, the dust 35 receptacle 28 is then filled with water to the proper depth and the motor is started. A disinfectant may be added to the water to kill the bacteria which may be trapped therein. Also a perfume may be added to the water to provide a deodorant. The suction produced by the fan causes 40 dust laden air to be drawn into the tangentially directed inlet 24 at the upper end of the casing 23. This causes the dust laden air within the casing to move spirally downward in the form of a whirling annulus of air. The arrows indicate 45 the motion of the air in the vertical plane. The dust in the air is thrown by centrifugal force to the outside of the casing where it gradually settles to the dust receptacle. The whirling annulus of air is in contact with the water in the dust 50 receptacle and causes a wave to be formed on the surface of the liquid which travels circumferentially around the dust receptacle. The general 55 position of the liquid in the dust receptacle at one instant is shown by the dotted line 44 in Fig. 3. At the right-hand side of the dust receptacle the liquid is below the normal liquid level. At the 60 left-hand side the liquid is raised into a wave diagrammatically shown at 45. This wave sweeps around the inside of the dust receptacle and washes the side walls of the dust receptacle.

I find that the wetted side walls of the dust 65 receptacle form surfaces which are very effective in trapping the dust, particularly the very fine dust, such as ragweed pollen and other fine plant pollen and bacteria. The washing action of the 70 wave sweeping around the side walls of the receptacle keeps these surfaces clean and wetted so that they do not lose their effectiveness and also sweeps the dust into the liquid in the receptacle 75 and traps the dust therein. The trapping of the dust in the liquid is important because otherwise the whirling motion of the air within the dust receptacle would cause the dust to be continually picked up by the air, and the dust would not be retained within the dust receptacle. Obviously, if

the dust in the receptacle were being picked up by the air, the centrifugal separation would be less effective.

Since the inside of casing 23 is at less than atmospheric pressure during the operation of the 5 cleaner, the joints between the casing and the dust receptacle and between the rubber ring 13 and flanges 36 and 35 are tightly sealed. The 10 pressure between these joints is such that the dust receptacle and the motor driven fan unit 10 cannot be removed during the operation of the cleaner.

The air is discharged from the casing through the slots 40 in the tube 39 upwardly through the tube, through the filter pad 37, to the inlet opening 15. From here, the air is discharged around the periphery of the fan through the space between the stationary member 2 of the motor and the casing 1, through the openings 16 in the casing, and downwardly around the lower edge of the 20 baffle 17. In passing through the slots 40, the air makes a turn of somewhat more than 90 degrees, and the particles of dust which may be in the air are thrown outwardly and do not pass through the slots. The suction in the tube 39 causes the 25 plate 41 to be drawn up against the lower end of the tube 39. This closes the end of the tube so that all air will pass through slots 40. It is desirable that the walls of the casing 23 be kept dry, as otherwise the dust would be held on the side 30 walls of the casing and the casing would have to be cleaned. Also the presence of dust on the side walls of the casing would increase the friction and thereby decrease the speed of the whirling air. The in-turned edge 27 of the dust receptacle 35 assists in keeping the side walls of the casing 23 dry. This in-turned edge prevents the circumferentially traveling wave on the surface of the liquid from rising above the dust receptacle, and directs the liquid in the wave inwardly, as indicated diagrammatically by the arrows 46.

The dust which is too fine to be centrifugally separated is kept within the tube 39 by the filter 37. When the cleaner is shut down, the plate 41 returns to the bottom line position of Fig. 3, and 45 this dust falls through the open end of tube 39 into the liquid in the dust receptacle. At the conclusion of the cleaning, the dust receptacle 50 may be removed and the contents emptied down a drain and the dust receptacle may then be re-filled with clean water.

In the modification shown in Fig. 5, the plate 41 is fixed to the lower end of the tube 39 and extends a considerable distance over the center of the liquid in the dust receptacle. This plate provides an area above the center of the liquid in which upward currents of air are prevented. These upward currents would interfere with the whirling motion of the air about the tube 39 and thereby interfere with the centrifugal separation 60 of the dust from the air. These upward currents might also cause the liquid in the dust receptacle to be lifted at the center and to be spattered over the inner walls of casing 23.

When vacuum cleaner is to be used as a source 65 of air pressure for operating paint sprayers or the like, the baffle 17 is turned down on the flange 18 so that the ring 19 is forced against the casing 1, sealing the space between the lower end of the baffle and the casing. Cap 47 is then removed 70 from tube 48 and a hose connected to the tube. Air is now forced through the hose. If desired, the unit may be removed from the sleeve 34 and supported on legs 49 which are formed on band 12.

What I claim as new and desire to secure by Letters Patent in the United States is:

1. In a vacuum cleaner, a casing having an inlet for dust laden air, means for producing a whirling annulus of the air within the casing which centrifugally separates the dust from the air, a discharge outlet from the casing including a hollow member extending into the center of the whirling air and having an opening at the lower end and openings in the side walls thereof, and a plate for covering the opening in the lower end of said member, said plate being biased downwardly and being drawn upwardly to cover the opening in the lower end of said member during discharge of air through said member.
2. In a vacuum cleaner, a vertical casing, a motor-driven fan mounted in and discharging to the casing, discharge openings spaced around the casing, a baffle depending around the openings and surrounding the casing for directing the discharged air downwardly to the outside air, means movably mounting the baffle on the casing whereby it is movable between a position in which its lower end is spaced from the casing and a position in which its lower end engages the casing to seal the space between the baffle and casing, and means providing a discharge outlet for the air under pressure between the baffle and the casing.
3. In a vacuum cleaner, a casing having a liquid containing dirt receptacle at the lower end, an inlet to the casing, suction means for drawing dirt-laden air through the casing inlet, means producing a whirling annulus of the air within the casing over the surface of the liquid of sufficient speed to cause a circumferentially traveling wave on the surface of the liquid sweeping the casing and walls, and a discharge outlet from the casing including a hollow member extending into the center of the whirling annulus of air, said member having a closed lower end above the surface of the liquid and having openings in its side walls arranged so that the air entering the openings must turn a sharp corner whereby dirt is separated from the air entering the openings.
4. In a vacuum cleaner, a casing having an inlet for dirt-laden air and a liquid containing dirt receptacle at the lower end thereof, suction means for drawing dirt-laden air through the casing inlet, means producing a whirling annulus of the air within the casing in contact with the surface of the liquid and the casing walls, a discharge outlet from the casing comprising a hollow member extending into the center of the whirling annulus of air, said member having openings in its side walls arranged so that the air entering the openings must turn a sharp corner whereby dirt is separated from the air entering said openings, and a baffle spaced below said openings and above the surface of the liquid at the center of the receptacle for preventing upward flow of air in the region of said openings.
5. In a vacuum cleaner, a casing having an inlet for dirt-laden air and a liquid containing dirt receptacle at the lower end thereof, suction means for drawing dirt-laden air through the casing inlet, means for producing a whirling annulus of the air within the casing in contact with the surface of the liquid and the casing walls, the air in said annulus rotating at sufficient speed to cause a circumferentially traveling wave on the surface of the liquid sweeping the casing walls, a discharge outlet from the

casing including a hollow member extending into the center of the whirling annulus of air, said member having openings in its side walls arranged so that the air entering the openings must turn a sharp corner whereby dirt is separated from the air entering the openings, and a baffle above the surface of the liquid and below said openings for preventing upward flow of air in the region of said openings.

6. In a vacuum cleaner, a chamber having a liquid containing dirt receptacle at its lower end, an inlet to the chamber above the liquid, means for producing a whirling annulus of air within the casing in contact with the surface of the liquid, and an outlet from the chamber including a hollow axially extending member depending within the whirling annulus of air and having openings in its side walls through which the air flows, said openings being arranged with respect to the air so that the air entering the openings must turn a sharp corner, the lower end of the outlet being closed and spaced from the upper surface of the liquid.

7. In a vacuum cleaner, a chamber having a liquid containing dirt receptacle at its lower end, an inlet to the chamber, an outlet from the chamber including a hollow member depending centrally therein and having openings in its side walls through which the air flows, said openings being arranged with respect to the air so that the air entering the openings must turn a sharp corner, the lower end of said member being closed and spaced above the surface of the liquid, and means for effecting relative rotation between said member and the air whereby the dirt is centrifugally separated from the air flowing through said openings.

8. In a vacuum cleaner, a casing having an inlet for dirt-laden air and a liquid containing dirt receptacle at the bottom, a tubular member depending within the casing providing an annular passage between it and the casing, openings in the side walls of said member for discharging air from the casing through said member, said openings being arranged with respect to the air so that the air entering the openings must turn a sharp corner, means for effecting relative rotation between the air and said member whereby the dirt is centrifugally separated from the air flowing through said openings, and means between said openings and the upper surface of the liquid for preventing upward flow of air in the region of said openings.

9. In a vacuum cleaner, a casing having an inlet for dust laden air, a suction nozzle for cooperation with the surface being cleaned, a passage leading from the suction nozzle to the casing inlet, suction means drawing dirt-laden air through said nozzle and passage to the casing inlet, a tubular member within the casing providing an annular passage between it and the walls of the casing, means producing a whirling annulus of air in said passage, a liquid containing dust receptacle below said tubular member, the upper surface of the liquid being spaced from said member, the surface of the liquid therein being in contact with said whirling air, and openings in the walls of said tubular member for discharging air from the casing through said tubular member, said openings being arranged so that the air entering the openings must turn a sharp corner whereby dirt is separated from said air.

10. In a vacuum cleaner, a casing having an inlet for dust laden air, suction means drawing

- 5 dirt-laden air through the casing inlet, a tubular member within the casing providing an annular passage between it and the walls of the casing, means producing a whirling annulus of air in said passage, a liquid containing dust receptacle below said tubular member, openings in the walls of said tubular member for discharging air from the casing through said tubular member, said openings being arranged so that the air entering the openings must turn a sharp corner whereby dirt is separated from said air, and a baffle between said openings and the surface of the liquid for preventing upward flow of air around said openings.
- 10 11. In a vacuum cleaner or the like, a casing, a hollow discharge member arranged within the casing to provide an annular passage between its side walls and the casing, an inlet at the upper end of the casing for directing dust laden air tangentially between said member and said casing, openings in the side walls of said hollow member at the lower end thereof arranged so that the air entering said openings must turn a sharp corner, and a dust receptacle at the lower end of said casing.
- 15 12. In a vacuum cleaner, a dust receptacle at the lower end, a motor driven fan above the dust receptacle, walls cooperating with the dust receptacle to provide a chamber below the fan and an inlet to the fan, said walls including walls of flexible material resiliently supporting the motor driven fan, an inlet to the chamber for dust laden air, a member within the chamber having openings through which the air flows to the fan inlet, and means producing relative rotation between said openings and the dust laden air, said openings being arranged so that the air entering the openings must turn a sharp corner whereby the dust is separated from the air flowing through the openings.
- 20 13. In a vacuum cleaner, a dust receptacle at the lower end, a motor driven fan above the dust receptacle, walls cooperating with the dust receptacle to provide a chamber below the fan and an inlet to the fan, an inlet to the chamber for dust laden air, means for producing a whirling annulus of air in the chamber, and a hollow member extending through the center of the whirling air and having openings in the side

walls thereof for conducting air from the chamber to the fan inlet, said openings being arranged so that air entering the openings must turn a sharp corner whereby dirt is separated from the air entering the openings.

5

14. In a vacuum cleaner, a casing having an inlet thereto, an annular member of flexible material supported at its outer edge from the casing, a motor driven fan supported on the inner edge of said member for withdrawing air from the casing, and means between the casing inlet and the motor driven fan and carried by said annular member for separating the dust from the air by forcing the air to turn a sharp corner.

15. In a vacuum cleaner, a casing having a dust receptacle at the lower end, a motor driven fan unit supported within the casing in spaced relation to the casing walls and having a fan inlet at the lower end, means sealing the space between the casing walls and the fan inlet providing a chamber including said dust receptacle, an inlet to the chamber for dust laden air, a member within the chamber having openings through which air flows to the fan inlet, and means producing relative rotation between said openings and the dust laden air, said openings being arranged so that the air entering the openings must turn a sharp corner whereby the dust is separated from the air flowing through the openings.

30

16. In a vacuum cleaner comprising, a casing having a liquid containing dust receptacle at the lower end, a motor driven fan unit supported within the casing in spaced relation to the casing walls and having a fan inlet at the lower end, means sealing the space between the casing walls and the fan inlet providing a chamber including said dust receptacle, an inlet to the chamber for dust laden air, a member within the chamber having openings above the liquid level in the dust receptacle through which air flows to the fan inlet, and means producing relative rotation between said openings and the dust laden air, said openings being arranged so that the air entering the openings must turn a sharp corner whereby the dust is separated from the air flowing through the openings.
